UNITED STATES PATENT OFFICE.

LEWIS J. ATWOOD, OF WATERBURY, CONNECTICUT.

LAMP-BURNER.

SPECIFICATION forming part of Letters Patent No. 324,067, dated August 11, 1885.

Application filed September 10, 1884. (No model.)

To all whom it may concern:

Be it known that I, LEWIS J. ATWOOD, of Waterbury, in the county of New Haven and State of Connecticut, have invented an Improvement in Lamp-Burners, of which the following is a specification.

Lamp-burners have been made with a cylindrical guide around the wick-tube, and upon this a sleeve-slide having arms that extend to the chimney-holder. In a burner of this kind the heat is liable to be conducted by the cylindrical guide down to the lower part of the wick-tube and to the reservoir.

My present invention has for its object the ventilation of the burner and the production of a guide that will give a regular amount of friction for holding the chimney in an elevated position, and for allowing it to be moved up or down with freedom and regularity.

20 In the drawings, Figure 1 is a vertical section of the lamp-burner complete, with the chimney-holder raised. Fig. 2 is a sectional plan at the line $\alpha\alpha$, and Fig. 3 shows the blank from which the guide is by preference formed.

25 The burner-base b and wick-tube a are of usual construction, and the foraminous shell c is generally provided for the chimney-holder d to rest upon when moved down to its normal position. e is the deflector resting at 30 its lower edge upon the chimney-holder.

The disk i is, by preference, perforated. It surrounds the wick-tube near its upper end, and between this and the base b there are the vertical guide-bars l . These are attached at 35 their bottom ends to the base b , and by preference they are made from bars that project from the edges of the disk-blank, Fig. 3, and are turned down parallel to each other and to the wick-tube.

40 The frictional slider n is provided with arms s , extending to the chimney-holder d . This slider n is around the bars l , and it is preferable to make said slider of a disk or plate with holes in it, through which the bars l pass, and 45 these holes are to be cut so that the tongues n'

will be turned down parallel with each other and form friction-guides, running against the surfaces of the bars l when the chimney-holder is raised or lowered. The air-distributer r is beneath the deflector and within and connected to the chimney-holder. 50

In this construction the disk i is above the slider n , and the parts cannot become separated. If, however, it is desired to lift the slider and chimney-holder off, then the slider 55 must be made as a ring outside and surrounding the range of bars l .

I do not claim guides around the wick-tube upon which the upper part of the lamp is guided as it is raised and lowered; and in my 60 applications Nos. 142,552 and 142,553, filed September 10, 1884, the chimney-holders and deflectors are capable of being elevated; but the peculiar devices for effecting that object differ from those herein described. 65

I claim as my invention—

1. The combination, with the flat wick-tube and the screw-base connected to the same, of a disk, i , around the upper part of the wick-tube, vertical bars connecting the same with 70 the base, a slider around the bars, a chimney-holder, and arms extending from the slider to such chimney-holder, substantially as set forth.

2. The combination, in a lamp-burner, of a screw-base, a flat wick-tube, a range of vertical bars around the wick-tube, the disk i , connecting the upper ends of the bars and the wick-tube, a slider having yielding frictional bearings upon such bars, a chimney-holder, and arms connecting the same to the slider 80 and the perforated air-distributer r , and the deflector e above the air-distributer, substantially as specified. 75

Signed by me this 30th day of August, A. D. 1884.

L. J. ATWOOD.
